UNITED STATES PATENT OFFICE.

WILLIAM H. ALLEN, OF DETROIT, MICHIGAN.

PROCESS FOR DRYING HIDES.

1,075,319.

Specification of Letters Patent.

Patented Oct. 14, 1913.

Application filed January 31, 1913. Serial No. 745,319.

To all whom it may concern:

Be it known that I, WILLIAM H. ALLEN, a citizen of the United States, and a resident of Detroit, in the county of Wayne 5 and State of Michigan, have invented a new and Improved Process for Drying Hides, of which the following is a specification.

This invention relates to the art of tanning leather and especially to that step 10 which embraces the drying of the hides after they are taken from the tanning vats, and the object of my invention is to provide a process for drying hides whereby the greatest possible area of merchantable 15 leather may be produced. It will be understood that this process may be used in the drying of any other fibrous material and is an advance over the process disclosed in my former Patent No. 1,009,881, dated Nov. 20 28th, 1911.

This invention consists of a process for drying fibrous material such as hides, comprising two steps; first, stretching the hides while wet on a flat plate to which they will 25 adhere until they become dry; and second, causing a current of air or other vapor-absorbing fluid to flow over each hide from the center outward so that the leather will remain wet and attached to the plate along its 30 edges while it is drying from the center outward, thus insuring a retention of the full area of the stretched hide.

This process may be carried out by the mechanism illustrated in the accompanying 35 drawing, in which—

Figure 1 is a plan of a plate with a hide stretched on it. Fig. 2 is a perspective view of the outer end of an air pipe. Fig. 3 is a side elevation and Fig. 4 is a front elevation of a rack and supported plates in position. Fig. 5 is a view, partly in elevation 40 and partly in section, of an air pipe.

Similar reference characters refer to like parts throughout the several views.

In putting this process into use, the hide 45 shown in Fig. 1 will be placed on the plate 2 while still wet, and stretched the amount desired. The plate may be smooth or figured according to the desired finished surface of the leather. As stated in my former 50 patent, no nails are necessary to hold the stretched fibrous material in position, as the adhesion between the wet fibrous material and the metal plates is sufficient to hold the material in position. If desired, the plates 55 may be coated with lacquer or enamel.

Pressing the fibrous material against the plates, as by means of rollers, conduces to the adhesion. If desired, the fibrous material may be covered with the porous mats 60 shown in my former patent. The plates may then be placed in a rack consisting of posts 3 and side strips or supports 4 between the posts, on which the plates 2 rest. Adjacent the rack is a pipe 5, of any desired 65 construction, from which the flat pipes 6 extend between the plates above the hides to the middle of the hides, as indicated in Fig. 1. An opening 7 in the bottom of each pipe 6 permits air or other moisture-absorbing 70 fluid to escape at the middle of the hide, whence the fluid flows out between the plates 1. The moisture-absorbing fluid saturates 75 itself as soon as possible, resulting in the hide drying first at the center. As the edges 80 cling to the supporting plate, the material cannot shrink intermediate the edges, and as a result, the hide when dry will have substantially the same area as when stretched wet.

While the preferred method of causing a current of moisture-absorbing fluid to radiate over the hide from the opening 7 will be to connect the pipe 5 to a source of air under pressure, this is not necessary, as the 85 pipe 5 may connect to the outer air and the apparatus may be in a closed case 9, indicated in dotted lines in Fig. 4, from which air may be drawn in any desired manner. The upper plate 10 may be stationary. The 90 distance between the plates should be small, one inch often being sufficient, but this distance must be determined by experiments as it varies with fibrous materials of different 95 character.

I claim.

1. The process of drying fibrous material which consists in stretching the same while wet on a flat plate and causing moisture-absorbing fluid to pass over the same from the 100 center outward.

2. The process of drying fibrous material which consists in stretching the same while wet on flat plates, stacking the plates parallel to each other and close together, and 105 conducting currents of moisture-absorbing material to substantially the middle of the plates so that it will pass out between the plates in all directions.

3. The process of drying fibrous material 110 which consists in stretching the same while wet on a flat plate and then absorbing the

moisture from the material by a proper fluid, beginning at substantially the center of the fibrous material and then continuing toward the edges.

- 5 4. The process of drying hides which consists in stretching the hide on a flat plate, placing the plate adjacent another which is of substantially the same size and spaced a short distance from it, and conducting a current of air to the middle of the hide so the middle of the hide will dry first and the

drying of the hide will continue toward the edges which will adhere to the plate until dried.

In testimony whereof I have signed this 15 specification in the presence of two subscribing witnesses.

WILLIAM H. ALLEN.
